ANTENNA MAST CLAMP

Donald H. Wells, Oregon, Ohio, assignor to S & A Electronics, Inc., Oregon, Ohio, a corporation of Ohio

Filed Mar. 10, 1965, Ser. No. 84,189

Term of patent 14 years

(Cl. D54—1)

The figure is a perspective view of an antenna mast clamp showing my new design.

The bottom is the same as the top and the two sides are identical.

The broken lines are for illustrative purposes only.

I claim:

The ornamental design for an antenna mast clamp, substantially as shown and described.
